3,775,540
CINNAMYL PHENOLS USEFUL AS
ANTIMICROBIAL AGENTS

Leonard Jurd, Berkeley, A. Douglas King, Jr., Martinez, and William L. Stanley, Richmond, Calif., assignors to the United States of America as represented by the Secretary of Agriculture
No Drawing. Original application Sept. 22, 1970, Ser. No. 74,485, now Patent No. 3,745,222, dated July 10, 1973.
Divided and this application Oct. 31, 1972, Ser. No. 302,622

Int. Cl. A01n 9/26

U.S. Cl. 424—341

1 Claim

ABSTRACT OF THE DISCLOSURE

Substances which are subject to microbial spoilage are preserved by addition of a cinnamyl phenol, e.g., 2-cinnamyl-phenol, 4-cinnamyl-phenol, 2-methoxy-4-cinnamyl-phenol, 2-cinnamyl-5-methoxy-quinol, etc.

This is a division of our copending application, Ser. No. 74,485, filed Sept. 22, 1970, now U.S. Pat. 3,745,222 issued July 10, 1973.

A non-exclusive, irrevocable, royalty-free license in the invention herein described, throughout the world for all purposes of the United States Government, with the power to grant sublicenses for such purposes, is hereby granted to the Government of the United States of America.

This invention relates to the preservation of substances which are normally subject to microbial spoilage. The objects of the invention include the provision of novel processes and compositions for accomplishing such preservation. Further objects of the invention will be evident from the following disclosure wherein parts and percentages are by weight unless otherwise specified. The abbreviation p.p.m. used herein refers to parts per million. Temperatures are given in degrees centigrade. The symbol ϕ is used herein to designate the phenyl radical.

In accordance with the invention it has been found that certain agents exhibit unexpected antimicrobial activity and are useful for preserving all kinds of materials which are normally subject to microbial spoilage. The agents in question are certain cinnamyl-phenols, and their antimicrobial activity is unusual and unexpected because it is not shared by closely-related phenol derivatives.

Generically, the agents in accordance with the invention have the structure—

where at least one but not more than three of the R's are hydroxy radicals, and the remainder of the R's are each independently selected from the group consisting of lower alkyl, lower alkoxy, and hydrogen.

The compounds of the invention are especially useful because they are active against many microorganisms in the categories of bacteria, yeasts, and molds. In other words, the compounds are not just active against one or a few organisms; rather, they display broad-spectrum antimicrobial activity.

Examples of particular compounds within the scope of

2

the invention are given below by way of illustration and not limitation:

4-Cinnamyl-phenol
(also known as
obtusastyrene)

2-Cinnamyl-phenol

2-Cinnamyl-4-methyl-phenol

2-Cinnamyl-4-methoxy-phenol

2-Methyl-4-cinnamyl-phenol

2-Methoxy-4-cinnamyl-phenol

4-Cinnamyl-resorcinol

2-Cinnamyl-5-methoxy-quinol

70

4-Cinnamyl-pyrogallol

The compounds of the invention display activities which are equal or even superior to those of widely-used antimicrobial agents. This is illustrated by the following: In general, the compounds of the invention are superior to such known agents as phenol, resorcinol, o-phenylphenol, and the alkali metal sorbates and benzoates. For instance, compounds of the invention, at concentrations of 12 to 25 p.p.m., were found to inhibit the growth of four bacteria (*Bacillus cereus*, *Sarcina lutea*, *Staphylococcus aureus*, and *Streptococcus lactis*) whereas to achieve the same effect it required 100 to 200 p.p.m. of o-phenylphenol, more than 800 p.p.m. of potassium sorbate, and more than 1000 p.p.m. of sodium benzoate.

Alkyl 4-hydroxybenzoates are well known to exhibit potent microbial activity. In general, the compounds of the invention display a superior activity as compared to these benzoates wherein the alkyl group contains less than seven carbon atoms. For instance, whereas the compounds of the invention at a concentration of 12 to 25 p.p.m. will inhibit the growth of the four bacteria noted above, it requires concentrations of 100 to 400 p.p.m. for the same result to be achieved with the C₁-C₅ alkyl 4-hydroxybenzoates. Moreover, it may be noted that the compounds of the invention have an advantage in that their water-solubility is higher than that of the higher alkyl (e.g., heptyl) 4-hydroxybenzoates, and that the compounds of the invention do not exhibit the strong and unpleasant odor which characterizes the said benzoates. Also, with respect to some microorganisms, the compounds of the invention inhibit growth when applied at levels less than required with the higher alkyl 4-hydroxybenzoates. This is the case, for example, with bacteria such as *Acaligenes faecalis* and *E. coli*, yeasts such as *Pichia chodati*, *Hansenula anomala*, and *Saccharomyces cerevisiae*, and molds including *Aspergillus flavus*, *A. niger*, *Penicillium chrysogenum*, *Rhizopus senti*, *Botrytis cinerea*, *Byssochlamys fulva*, and *Alternaria* sp.

Of the various compounds included within the scope of the invention, the cinnamyl-substituted monophenols display particularly high antibiotic activity against a large variety of different microorganisms, and therefore are preferred with respect to the cinnamyl derivatives of di- or tri-phenols. Coming into special consideration is 4-cinnamyl-phenol because it displays antibiotic activity over a wide range of pH. The cinnamyl derivatives of monophenols are also preferred because they are essentially colorless, whereas those derived from di- or tri-phenols exhibit various shades varying from red to brown.

As evident from the explanation immediately following Formula I above, the invention includes compounds wherein there may be nuclear lower alkyl or lower alkoxy substituents in addition to the hydroxy groups. In general, the compounds are preferred wherein such additional substituents are absent or, if present, are in small number, e.g., a total of one or two lower alkyl and/or lower alkoxy substituents. Taking the foregoing facts into consideration, we prefer to employ the compounds of the sub-generic category represented by the formula—

wherein—

- R' is lower alkyl,
R'' is lower alkoxy,
n is an integer from 0 to 2,
5 m is an integer from 0 to 2, and
the sum of n and m is not more than 2.

The invention encompasses not only the use of any of the above-described agents individually, but also mixtures thereof.

In preserving substances in accordance with the invention, any of the aforesaid agents or mixtures thereof are incorporated with the substance, using an amount of the agent to inhibit microbial growth. Additional conventional treatments such as dehydration, canning, refrigeration, or freezing may be applied to the substance containing the added agent. The incorporation of the agent with the substance may involve a mixing of the substance and the agent—this is especially suitable where the substance is in liquid or particulate form. Where the substance is in the form of pieces of large dimensions the agent may be incorporated therewith by coating it on the surface of the pieces. For such purpose the agent is preferably dispersed in a carrier—a liquid such as water, alcohol, water-alcohol blends, oils, or a finely-divided solid such as salt, starch, talc, or the like.

The invention is of wide versatility and can be applied for the preservation of all kinds of substances which are normally subject to microbial spoilage. Typical examples of such substances are listed below by way of example. 30 Foodstuffs such as fruits, vegetables, juices, milk, eggs, meat, fish, grains, cereal products, cheese, etc. Animal glues and mucilages; dextrans; starch pastes and solutions; 35 cosmetic, medicinal, and dental preparations; vitamin preparations; pastes, solutions, or other preparations of natural gums such as tragacanth, Arabic, acacia, karaya, locust bean, agar-agar, pectin, elgin, etc.; fermentation broths, mashes, and residues from fermentation processes; whey; wines and vinegars; animal feeds and ingredients of animal 40 feeds such as fish meals, blood meals, feather meal, meat scraps, bone meal, tankage, grains, and oil-seed meals; proteins and protein hydrolysates; textile printing pastes; paints containing proteins or other spoilable dispersing agents; solutions of bark extracts or other tanning agents; 45 molasses; byproducts or wastes that contain potentially valuable carbohydrate, proteinous or fat ingredients such as stick liquor, corn steep liquor, fruit cannery wastes, citrus peels, cull fruit and vegetables, tops of root vegetables, distillers' slops, pulp liquors, wash water from textile de-sizing operations, waste liquors from wool scouring plants, dairy and slaughter house wastes and liquors, etc.

The compounds of the invention may be synthesized by known procedures—for example, those disclosed by Hurd et al., *Jour. Am. Chem. Soc.*, vol. 59, pp. 107-109; Barnes et al., *Tetrahedron*, vol. 21, pp. 2707-2715; Jurd, *Experientia*, vol. 24, pp. 858-860; Jurd, *Tetrahedron*, vol. 25, pp. 1407-1416; and Jurd, *Tetrahedron Letters* No. 33, pp. 2863-2866. Typically, these syntheses involve condensing 50 a selected phenol (phenol itself, a cresol, resorcinol, guaiacol, hydroquinone monomethyl ether, etc.) with cinnamyl bromide or cinnamyl alcohol.

The invention is further demonstrated by the following illustrative examples. For comparative purposes, various 65 compounds, including some of known antimicrobial activity, are included in the reported experiments.

EXAMPLE 1

A series of compounds were assayed for effectiveness 70 against bacteria, molds, and yeasts, using the following test procedure.

All compounds were tested at a concentration of 500 p.p.m. (w/v.). Plates were prepared by adding a measured amount of the candidate compound (in an appropriate solvent, i.e., acetone, ethanol, or water) to 10 ml. of steri-

lized medium, mixing thoroughly, pouring into 60 x 15 mm. Petri dishes, and allowing the gel to set. The plates were then inoculated with the test organisms. In the case of bacteria and yeasts the inoculation was done by Lederberg's replica plating technique, applying nine bacteria or seven yeasts on each plate. In the case of molds, drops of homogenized culture were placed on the surface of the plates, applying three to four molds per plate.

The plates were incubated at 28° C. for one to five days and evaluated by comparison with the controls.

The results are expressed on the basis:

- 5 + for effective to inhibit growth
± for not completely effective;
faint growth occurs
— for ineffective; growth occurs

The results are summarized in the following tables.

TABLE I
Activity of Various Compounds (at concentration of 500 p.p.m.) Against Bacteria

<i>Alternaria</i> sp.	+	+	+	—	—	—	±	+	+	—

The media used were: plate count agar (Difco) for bacteria; potato dextrose agar (Difco) for yeasts and molds.

Control plates were also prepared containing the media plus the same solvent used for the candidate agents and inoculated with the same organisms.

EXAMPLE 2

50 A series of compounds were assayed for effectiveness against bacteria, molds, and yeasts as set forth in Example 1, except that in this case the assays were conducted with varying amounts of each compound to determine the minimum concentration thereof required to inhibit growth.

The results are set forth in the following tables.

TABLE IV
Minimal Inhibitory Concentrations (in p.p.m.) of Various Compounds Against Molds

	4-cinnamyl-phenol	2-cinnamyl-4-methoxy-phenol	2-methyl-4-cinnamyl-phenol	2-cinnamyl-4-methyl-phenol	Ortho-Phenyl-phenol	Potassium sorbate	Sodium benzoate

<i>Botrytis cinerea</i>	25-50	50-100	50	100	100-200	100	100
<i>Byssochlamys fulva</i>	25	>200	100	100	200	200	>200
Alternaria sp.	25	50-100	50	50	100-200	100	>200

EXAMPLE 3

Two compounds (4-cinnamyl-phenol and 4-cinnamyl-resorcinol) were assayed for effectiveness against bacteria, molds, and yeasts, except that in this case the assays were conducted at different concentrations of each compound and at different pH's in order to determine the minimum concentration of each compound required to inhibit growth at the particular pH.

The results are tabulated below.

EXAMPLE 4

Samples of fruit juice (grape and apple) with and without added 4-cinnamyl-phenol were inoculated with cultures of wild yeast or pure wine yeast (*S. cerevisiae*) and held at room temperature. The inoculated juices were observed at intervals to detect the time at which fermentation (gas production) began. This is a measure of microbial activity—where the organisms multiply freely, the time for initiation of fermentation is short; conversely,

TABLE IX
Influence of 4-Cinnamyl-phenol on Fermentation of Fruit Juice Inoculated with Yeasts

Run	Substrate	Inoculum	Amount of inoculum, cells/ml.	Time for initiation of fermentation, hours					
				Zero 4-CP	12.5 p.p.m. of 4-CP	25 p.p.m. of 4-CP	50 p.p.m. of 4-CP	100 p.p.m. of 4-CP	200 p.p.m. of 4-CP
1	Grape juice	Wild yeast	10 ⁷	7	N.D.	12	N.D.	44	N.D.
2	do	do	10 ³	17	17	30	62	>96	N.D.
3	do	Wine yeast	10 ⁵	12	22	45	146	∞	∞
4	do	do	10 ²	41	75	∞	∞	∞	∞
5	Apple juice	do	10 ⁶	46	42	76	∞	∞	∞

Explanation of symbols:

4-CP designates 4-cinnamyl-phenol.

N.D. means not determined.

∞ means that fermentation did not occur; the organisms had been destroyed.

Having thus described the invention, what is claimed is:

1. A process for inhibiting the growth of microorga-

ing to said substance an effective microbial-growth-inhibiting amount of 2-cinnamyl-5-methoxy-quinol.
